H. C. HARRISON

PHONIC DIAPHRAGM

Filed June 19, 1923

Inventor:
Henry C. Harrison
by Jel L. Palmer Atty

UNITED STATES PATENT OFFICE.

HENRY C. HARRISON, OF PORT WASHINGTON, NEW YORK, ASSIGNOR TO WESTERN ELECTRIC COMPANY, INCORPORATED, OF NEW YORK, N. Y., A CORPORATION OF NEW YORK.

PHONIC DIAPHRAGM.

Application filed June 18, 1923. Serial No. 646,307.

The invention relates to phonic diaphragms and has for an object to provide a diaphragm of such configuration that it will be stiff in both radial and axial directions. The invention is not realized by a diaphragm having concentric circular corrugations for the reason that such a diaphragm, while stiff in radial directions, has not the required stiffness in an axial direction, that is, a direction along a line passing through the center of the diaphragm and at right angles thereto.

The object of the invention is accomplished by providing a diaphragm having corrugations such that any straight line drawn across the diaphragm, or any circle drawn on the diaphragm about any center on the diaphragm will cross a corrugation.

For further details, reference may be made to the drawings in which Fig. 1 is a cross-sectional view of such a diaphragm when employed as a loud speaker. Fig. 2 is a front elevation of the diaphragm in Fig. 1. Fig. 3 is a front elevation partly in section of a composite diaphragm made up of two diaphragms such as shown in Figs. 1 and 2. Fig. 4 is a sectional elevation of Fig. 3. Fig. 5 is a sectional elevation of a conical diaphragm having an unsupported periphery and corrugated as in Fig. 2. Fig. 6 is an enlarged view of the corrugations.

Referring in detail to the drawings, the diaphragm 1 may be of thin, stiff material such as paper or metal, and has closely spaced zig-zag corrugations of the form shown in detail in Fig. 6. In case the periphery of the diaphragm 1 is to be clamped, as shown in Figs. 1 and 2, the peripheral portion 2 of the diaphragm is preferably not corrugated. The diaphragm portion 2 then provides a flexible section between the rigid diaphragm 1 and the support 3. The diaphragm may be driven at its center by any suitable drive such as the electromagnetic device 4 which is shown and described in detail in Egerton Patent No. 1,365,898—January 18, 1921.

Figs. 3 and 4 show a modification wherein two diaphragms 5 and 6 having corrugations, as in Fig. 6, are fastened to an intermediate disc 7 which is carried by the support 3. In this case the corrugations in diaphragm 5 extend generally at right angles to the corrugations of diaphragm 6, as

illustrated in Fig. 3. If the diaphragms 5 and 6 are of metal such as aluminum then the intermediate disc 7 may be of the same or similar material, and the diaphragms 5 and 6 may be fastened, for instance, by spot welding to the disc 7. If desired, however, the diaphragms 5 and 6 and the diaphragm 1 as well, may be of any other suitable light, stiff material such as paper. In this case the disc 7 may be of paper or similar material and the parts 5, 6 and 7 may be fastened together by means of glue or the like.

The diaphragm 8 in Fig. 5 has corrugations as shown in Fig. 6 and may be of the materials described above. This diaphragm is illustrated as a cone supported at its apex 70 by a driving rod 9 of the electromagnetic device 4.

All of the diaphragms above described are large direct acting diaphragms of the order of a foot or more in diameter and they 75 may act to directly set the air into vibration without the use of a restrictive device such as a horn.

If the diaphragm is of metal the corrugations may be formed by stamping or the like. If it is of material such as paper they may be formed either during the process of manufacturing the textile sheet or afterwards by dampening a flat sheet and pressing it into a corrugated die.

What is claimed is:

1. A composite phonic diaphragm comprising a plurality of corrugated diaphragms, the corrugations of one of said diaphragms crossing the corrugations of another of said diaphragms.

2. A large direct acting phonic diaphragm having a plurality of parallel discontinuous ridges so positioned that the crest of the ridges form only zig-zag lines consisting of short straight line sections serially connected and extending in one general direction.

3. A large direct acting phonic diaphragm made of sheet material having formed therein a plurality of parallel broken series of corrugations, the break in each adjacent row being staggered and each row being connected with the adjacent row by a plurality of parallel corrugations placed at an angle 100 to the first series of corrugations.

4. A large direct acting diaphragm formed of thin sheet material and having its

surface made up into zig-zag corrugations extending across the diaphragm, the zig-zag corrugations being generally parallel and mutually independent.

5. A large direct acting diaphragm comprising a sheet of thin material having in its surface a multiplicity of corrugations in the form of zig-zag ranges, each range con-

sisting of short straight line ridges joined end-to-end and at an angle to one another, to each range being separated from the adjacent range throughout its extent by a similarly shaped valley.

In witness whereof, I hereunto subscribe my name this 15 day of June A. D., 1923.

HENRY C. HARRISON.
